UNITED STATES PATENT OFFICE.

GUSTAV SCHEEL, OF BERLIN, GERMANY, ASSIGNOR TO TELEGRAPHIE-GESELLSCHAFT
MIT BESCHRÄNKTER HAFTUNG SYSTEM STILLE, OF BERLIN, GERMANY.

MAGNETIC TALKING, DICTATING, AND LIKE MACHINE.

Application filed December 4, 1922, Serial No. 604,870, and in Germany December 10, 1921.

This invention relates to magnetic talking, dictating and like machines of the kind in which, according to the Poulsen system, the record is taken by a steel wire that is run between two sets of opposing electromagnets.

The object of the invention is so to construct and arrange the magnet holders that they can easily be separated from one another and from the machine frame, thereby facilitating, on the one hand the introduction of the steel wire and on the other hand the renewal of worn-out magnet cores.

This object is achieved according to the invention by the provision of a carrier connected to the machine frame and adapted to receive the magnet holders, the latter being detachably connected to the carrier so that they can easily be removed. Only one of the holders is directly connected to the carrier, the other being secured in position by means of locking elements which are connected to the carrier and which can readily be unfastened for releasing the holder and for admitting the wire. Current is supplied to the magnets through contact springs which make the contact automatically when the holders are placed in the carrier. The magnet cores are held in position by cover plates whose fastening elements can also be readily turned open for releasing the plates when a renewal of the cores is required.

Fig. 1 of the drawings represents a side view of the device constructed according to the invention.

Fig. 2 is a plan of the same,

Fig. 3, a longitudinal section showing one cover plate and the magnet cores detached,

Fig. 4, an end view of the separated magnet holders,

Fig. 5, a plan of the holders with removed cover plate,

Fig. 6, a side view of the carrier alone, and

Fig. 7 is a diagram of the electric connections.

With reference to Fig. 3 it will be seen that the device is composed of two superposed magnet holders 1 and 2 whose relative position is determined by two studs 13 which are fixed to one holder and which engage apertures 20 in the other holder by means of split projecting heads. Each holder contains a magnet composed of electric coils 3 and 4 and cores 5 and 6. Each

pair of cores is connected to a yoke 7 by means of which the cores can easily be applied and removed. When in use, the cores are held in position by a blade spring 12 which presses the yoke 7 against the magnet spools. The spring 12 is connected to a plate 9 which covers the magnet coils and which is locked in position by a bar 10. The latter turns about the stem of a knob 22, whereby the cover plate is handled, and locks the plate by engagement with headed screws 11 secured to the magnet holder. The screws 11 project beyond the surface of the cover plate which is formed with notches for their admission.

The record wire 8 passes between the two magnet holders which, together with the heads of the screws 13, are grooved to form a passage for the same. The magnet cores project into the wire passage and are slit to admit the wire, the magnets being arranged in a staggered position so that both pairs of cores can enter the wire passage.

The magnet holders are connected to a carrier which may have the form of a frame 15 and which is secured to a support 23 on the machine frame. The frame 15 embraces the lower magnet holder 2 which is secured thereto by means of screws 16 passing transversely through the elements. For fastening the upper magnet holder 1, there are two arms 18 pivoted to the side members of the frame so that they can be turned, like hasps, into engagement with headed screws 19 connected to the holder 1.

When a fresh wire is to be introduced into the device, the arms 18 are simply turned out of engagement with the screws 19 so that the holder 1 can be lifted off. This, as well as the refastening of the holder after the introduction of the wire, is an easy operation. When the cores are worn by the friction with the wires and therefore require renewal, it is only necessary to turn the bars 10 about their pivots so as to release the cover plates 9, whereupon the latter can be removed and the cores taken out. In case of a renewal of the lower pair of cores, it may be more convenient to remove the holders from the carrier 15, which is easily effected by a detachment of the screws 16.

The ends of the upper magnet coils are connected to plug terminals 14 (Fig. 7),

and corresponding socket terminals, which receive the plugs when the holders are assembled, are electrically connected with contact springs 17, two direct and two through the lower magnets. The springs 17 are fitted at one end of the holder 2 so as to engage contact pieces 24 on the support 23 for collecting current from the same, when the holder is placed in the carrier 15. With the holder 2 in its proper position in the carrier, the tension of the springs 17 is enough to ensure a safe electric contact.

I claim:—

1. In a magnetic talking, dictating or like machine of the character described, the combination with two superposed magnet holders, of a carrier for such holders secured to the machine frame, and means for connecting the holders to the carrier so that both holders can be removed together, substantially as and for the purpose set forth.

2. In a magnetic talking, dictating or like machine of the character described, the combination with an upper and a lower magnet holder, of a carrier frame embracing the lower holder and being itself secured to the machine, and means for securing the lower holder being connected to the carrier frame so that both holders will be free for removal after the detachment of the lower one.

3. In a magnetic talking, dictating or like machine of the character described, the combination with two superposed magnet holders and with magnet coils fitted in said holders, of magnet cores loosely arranged in

said coils, detachable plates connected to the holders so as to cover the magnets, springs connected to said plates so as to bear against the cores and hold them in position, a carrier connected to the machine, and means for securing the magnet holders to said carrier so that both can be detached therefrom together and so that one holder can be removed without disturbing the other one, substantially as and for the purpose set forth.

4. In a magnetic talking, dictating or like machine of the character described, the combination with two superposed magnet holders and with magnet coils fitted in said holders, of magnet cores arranged loosely in said coils, plates connected to the holders so as to cover the magnets, springs connected to the plates so as to bear against the cores and hold them in position, a carrier connected to the machine, means for connecting the lower holder detachably to said carrier, means for clamping the upper holder to the lower one and to the carrier, so that one holder can be removed without disturbing the other and so that both can be removed together from the carrier, contact springs connected to the lower holder so as to make contact for collecting energizing current when the holder is placed in the carrier, and plug contacts connected to the upper holder for collecting current from the lower one, substantially as set forth.

GUSTAV SCHEEL.
